UNITED STATES PATENT OFFICE

122,595

DESIGN FOR AN ORGAN CASING

George P. Gubbins, Oak Park, Ill.

Application August 22, 1939, Serial No. 86,832

Term of patent 7 years

To all whom it may concern:

Be it known that I, George P. Gubbins, a citizen of the United States, residing at Oak Park, in the county of Cook and State of Illinois, have invented a new, original, and ornamental Design for an Organ Casing, of which the following is a specification, reference being had to the accompanying drawing, forming part thereof.

Figure 1 is a perspective view of the organ cas-

ing, showing my new design in opened position; and

Figure 2 is a fragmentary perspective view of the upper portion of the organ casing, in closed position.

I claim:

The ornamental design for an organ casing, as shown.

GEORGE P. GUBBINS.
